UNITED STATES PATENT OFFICE.

ROY L. ARTHUR, OF LANE, ILLINOIS, ASSIGNOR TO ELI C. HERSCHEBERGER, OF ARTHUR, ILLINOIS.

HOOF-CLIPPER.

1,136,991.

Specification of Letters Patent. Patented Apr. 27, 1915.

Application filed May 25, 1914. Serial No. 840,693.

To all whom it may concern:

Be it known that I, ROY L. ARTHUR, a citizen of the United States, a resident of Lane, in the county of DeWitt and State of Illinois, have invented certain new and useful Improvements in Hoof-Clippers, of which the following is a specification.

My invention relates to improvements in hoof clippers, and has for its principal object the provision of such a device which is simple in construction, easy to operate and efficient in producing good results in the hands of an experienced workman.

A further object is the provision of a hoof clipper in which the knife coöperating jaw is first moved under the hoof of an animal, and then the knife forced downwardly to clip the hoof.

Further objects include improvements in details of construction and operation.

To the accomplishment of the foregoing and such other objects as may hereinafter appear, my invention consists in the construction, combination and arrangement of parts hereinafter described and then sought to be defined in the claims, reference being had to the accompanying drawings forming a part hereof, and which show for illustrative purposes a preferred embodiment of my invention, it being understood however that various changes may be made within the scope of the claims without digressing from my inventive idea.

In the drawings:—Figure 1 represents a side elevation of a device constructed according to my invention in position ready to begin operation; Fig. 2 is a similar view of the operating parts at the completion of their operation; Fig. 3 is a view similar to Fig. 1, of the other side of the device.

Referring now to the drawings, the numeral 1 designates one of the handle members which forms or constitutes what might be called a base member, having its end provided with the enlarged transverse member 2, having the sharpened lower edge 3 and depending extension 4 for the purpose of providing an anchorage or bearing for the device when in operation, as will be explained later. This handle member is provided with a longitudinally extending slot 5, intermediate its ends, and has its other end bifurcated or forked as at 6, to receive a portion of the other handle or operating member 7. Mounted so as to slide relative

to said handle or base member 1, is the knife carrying member 8, having the spaced side members 9 extending along said handle or base member, which are connected by means of a pin 10, which is loosely slideable in slot 5. The head of this member 8 is provided with the knife member 11, as shown. The handle member 7 is pivotally connected to this member 8 by means of the pin 12 which passes through the boss or sleeve 13, on the end of said handle member 7. A pin 14 passes through the bifurcated or forked ends 6 of the handle or base member 1, pivotally connecting it to said handle member above the boss or sleeve 13. The handle member 7 is then bent to extend at an angle, as indicated at 15, and to this portion is pivotally connected, as by means of pin 16, member 17 which carries the jaw or blade to coöperate with the knife 11. This member 17 has its end bifurcated as at 18, to embrace the inclined portion 15 of the handle 7, and the pin 16 passes therethrough, forming a pivotal connection. The lower portion of this member 17 is formed of peculiar shape as shown in the figures of the drawing having its one face formed on a double curve providing seat 19 and the inclined portion 19' while the other face has the two inclined portions 20 and 20'. The foot 21 has the knife member 21' attached thereto, the latter being preferably of drop forged steel while the member 17 is of malleable casting. The pins 22 are secured to member 8 and positioned on opposite sides of the lower portion of member 17. These pins coöperate with the above described surfaces of the member 17 to produce the proper movement and coaction between the knife carrying members as will be described later.

Secured to the pin 16 is the pruning knife member 23 which is pivoted intermediate its ends on pin 12, having the lower portion formed with the convex knife edge 24, which coöperates with a correspondingly curved concave portion 25, on the adjacent side member 9, of member 8. This provides the pruning knife or tree trimmer.

Apertures 26 and 27 are provided in the handle members 1 and 7 for the purpose of attaching extensions to facilitate the operation of the device for either of its purposes.

In operation as a hoof clipper the device is placed in the position shown in Fig. 1,

with the foot of the operator on the rear portion of the base member 1, thus forcing the extension 4 into the ground to anchor the device. The handle member 7 is then moved downward, which operation first causes the knife member 21, 21' to move forwardly under the hoof of the animal, this movement being caused by the engagement of the pin 22 with the inclined surface leading from seat or recess 19, it being noted that member 17 is pivotally connected to handle 7. When this pin passes the apex 19'', the knife 11 is caused to descend rapidly in a substantially vertical direction, and will clip the hoof of the animal.

The operation of the device as a pruning knife or tree trimmer is obvious. The simplicity of structure renders the article cheap to manufacture and efficient in operation.

20 What I claim is,—

1. In a device of the character described and in combination, a pair of handle members pivotally connected together, one of which forms a base member, a knife carrying member having a slidable and pivotal connection with one of said handle members and a jaw or anvil member pivotally connected to the other of said handle members and adapted to coöperate with said knife carrying member, said jaw or anvil member having one face formed on two inclines converging to an apex and a pin connected to said knife carrying member engaging said face whereby a slidable and pivotal connection between said members is provided.

2. In a device of the character described and in combination, a pair of handle members pivotally connected together, one of which forms a base member, a knife carrying member having a slidable and pivotal connection with one of said handle members and a jaw or anvil member pivotally con-

nected to the other of said handle members and adapted to coöperate with said knife carrying member, said jaw or anvil member having its edge faces each formed on a plurality of inclines and a plurality of pins connected to said knife carrying member and positioned on opposite sides of said jaw or anvil member to engage said edge faces thereof, whereby a slidable and pivotal connection between said members is provided. 45

3. In a device of the character described and in combination, a pair of handle members pivotally connected together, one of 55 which is adapted to serve as a base member, a knife carrying member having a slidable and pivotal connection with said base member, the other of said handle members also having a pivotal connection with said knife 60 carrying member, said knife carrying member being formed with spaced side members and a pin connection at the ends of said spaced side members to said base member to form said slidable and pivotal connection, 65 a jaw or anvil member extending between said spaced side members of said knife carrying member and pivotally connected to the other of said handle members, said jaw or anvil member having its edge faces each 70 formed on a plurality of inclines and a plurality of pins connected to said knife carrying member and positioned on opposite sides of said jaw or anvil member to engage said edge faces thereof, whereby a slidable 75 and pivotal connection between said members is provided. 75

In testimony whereof I sign my name in the presence of two subscribing witnesses.

ROY L. ARTHUR.
